UNITED STATES PATENT OFFICE.

JOHN E. RED, OF WORTHAM, TEXAS.

NON-REFILLABLE BOTTLE.

1,100,813.

Specification of Letters Patent. Patented June 23, 1914

Application filed August 23, 1913. Serial No. 786,326.

To all whom it may concern:

Be it known that I, JOHN E. RED, a citizen of the United States, residing at Wortham, in the county of Freestone and State of Texas, have invented certain new and useful Improvements in Non-Refillable Bottles, of which the following is a specification, reference being had therein to the accompanying drawing.

This invention relates to a non-refillable bottle and the principal object of the invention is to provide an improved bottle having an improved valve which is held in position by the cork which forms a stopper for the bottle.

Another object of the invention is to so provide the bottle neck that the valve ball will be positioned in a central compartment having grooves leading therefrom, through which the contents of the bottle may flow when the bottle is turned in the proper position.

Another object of the invention is to provide the bottle with an improved valve having a perforated plate which forms a guide for the stopper engaging plunger and constitutes means for preventing the removal of the plunger.

With these and other objects in view this invention consists of certain novel combinations, constructions and arrangements of parts as will be hereinafter fully described and claimed.

This invention is illustrated in the accompanying drawing; wherein:

Fig. 1 is a vertical sectional view of the bottle provided with the improved valve; Fig. 2 is a view similar to Fig. 1 with the bottle turned in a position to permit the contents to run out; Fig. 3 is a transverse sectional view through the bottle neck along the line 3-3 in Fig. 1; Fig. 4 is a perspective view of the perforated plate which is mounted in the bottle neck; Fig. 5 is an enlarged perspective view of the plunger.

The bottle 10 has its neck 11 thickened, as shown at 12, and is provided with a circular valve seat 13. The neck is provided with a recessed opening 14 leading from the valve seat 13 and forming a passage way in which the valve ball 15 is slidably mounted. This passage way 14 is provided with a plurality of $\frac{1}{4}$ in. grooves 16 which grooves extend as shown in Fig. 1 and it is so that when the bottle is turned to the position shown in Fig. 2, the contents of the bottle

can flow through these grooves and out of the bottle. If it were not for these grooves the ball 15 would close the passage 14 and prevent the liquid in the bottle from flowing out. A chamber 17 is formed in the neck between the outer end of the passage 14 and the inner end of the discharge opening 18 in which the cork 19 is seated and is of the same diameter as the distance between the outer edges of the grooves 16, thus forming an overhanging flange 20.

A plate 21 which is shown in Fig. 4 is placed within the chamber 17 and is provided with a reduced neck 22 so that the plate may be compressed a sufficient amount to permit it to be forced through the opening 18 into the chamber 17. This plate is formed from resilient material and returns to its normal position after entering the chamber 17, thus preventing the plate from being removed. It should also be noted that by having the end portions of the plate curved they will conform to the contour of the bottle neck and thus permit the plate to conform to the sides of the bottle and be more firmly held in position. The end portions of the plate are provided with openings 23 through which the contents of the bottle can flow when the bottle is turned to the position shown in Fig. 2. A plunger 24 passes through an opening 25 in the neck 22 and is provided with a cup-shaped inner head 26, which cup-shaped head 26 engages the ball 15 and holds the ball tight against the valve seat 13 when the stopper 19 is in position. This stopper 19 engages the head 27 at the outer end of the plunger 24 and forces the plunger inwardly against the tension of the spring 28. When the stopper 19 is removed the spring will contract, thus drawing the head 26 away from the valve ball 15 and permitting the valve ball to pass to the position shown in Fig. 2, so that the liquid can flow out of the bottle. It is preferred to have the ball valve ground and the seat 13 ground so that when the ball is forced upon the valve seat an air-tight joint will be formed. After the plate 21 has been put in place it will be impossible to remove the same, and therefore, the bottle cannot be refilled since the glass ball 15 will fall back upon the seat 12 and prevent the liquid from flowing into the bottle when the bottle is in the position shown in Fig. 1.

What is claimed is:

1. A bottle having its neck provided with

- a reduced passage-way communicating with an enlarged chamber and being also provided with side grooves leading from the passage and communicating with the chamber, the outer end of the bottle neck being provided with a discharge opening of less diameter than the chamber to provide an everhanging flange, a valve ball in the passage-way of said neck fitting against the valve seat at the inner end of the passage-way, a perforated resilient plate forced into said chamber through the discharge opening, a plunger passing through the plate, a cup-shaped head at the inner end of the plunger engaging said valve ball, and a spring carried by said plunger between said plate and head, and normally drawing the head toward the plate.
2. A bottle having its neck provided with a passage-way having a valve seat at its inner end communicating with an enlarged chamber formed in the neck, the neck being also provided with side grooves leading from the passage-way and communicating with the chamber, a resilient perforated plate positioned within the chamber and provided with a reduced neck, a plunger passing through the reduced neck, a valve ball within said passage-way, a head at the inner end of said plunger for engaging the ball to hold the same against the valve seat at the inner end of the passage, a resilient means between
- said plate and head for normally holding the plunger out of engagement with said valve ball, said plunger extending into the outer portion of the bottle neck whereby the outer end of the plunger will be engaged by a stopper inserted in the neck and moved inwardly in engagement with the valve ball and hold the same against the valve seat.
3. A bottle having its neck provided with a reduced passage communicating with an enlarged chamber having an abutment flange at its outer end, the neck being also provided with side grooves leading from the passage and communicating with the chamber, a valve ball slidably mounted in the passage, a plate in said chamber, a plunger slidably connected with said plate and having its inner end extending into said passage and its outer end extending into the outer portion of said neck whereby a stopper placed in the outer portion of the neck will engage the plunger and force the same inwardly to hold the valve ball against the valve seat at the inner end of the passage, and resilient means for normally holding plunger out of engagement with said valve ball.

In testimony whereof I hereunto affix my signature in presence of two witnesses.

JOHN E. RED.
